117,185, 117,186, 117,187, and 11788, all Feb. 19,
1971. This application Apr. 13, 1972, Ser. No. 243,917

Term of patent 14 years

Int. Cl. D24—01

U.S. Cl. D24—1 B

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

This is a continuation of design application Ser. Nos. D.117,187; D.117,185; D.117,186; D.117,187; and D.117,188, filed Feb. 19, 1971 and now abandoned.

FIG. 1 is a front perspective view of a dental operatory showing our new design;

FIG. 2 is a top plan view of the base cabinet portion;
FIG. 3 is a side elevation of FIG. 1;

FIG. 4 is a front perspective view of a second modified form of the dental operatory illustrated in FIG. 1;

FIG. 5 is a top plan view of the base cabinet portion;
FIG. 6 is a side elevation of FIG. 4;

FIG. 7 is a front perspective view of a third modified form of the dental operatory illustrated in FIG. 1;

FIG. 8 is a top plan view of the base cabinet portion;
FIG. 9 is a side elevation of FIG. 7;

FIG. 10 is a front perspective of a fourth modified embodiment of the dental operatory illustrated in FIG. 1;

FIG. 11 is a top plan view of the base cabinet portion;

FIG. 12 is a side elevation of FIG. 10;

FIG. 13 is a front perspective of a fifth modified embodiment of the dental operatory illustrated in FIG. 1;

FIG. 14 is a top plan view of the base cabinet portion;
and

FIG. 15 is a side elevation of FIG. 13.

We claim:

The ornamental design for a dental operatory, substantially as shown and described.
